UNITED STATES PATENT OFFICE

WALTER PORANSKI, OF CHICAGO, ILLINOIS

VANITY CASE

Application filed November 10, 1930. Serial No. 494,637.

The invention relates to compacts or vanity cases adapted to contain toilet goods such as face powder, rouge, puffs, mirrors, etc., of such a size as may be easily carried in a hand-bag, purse, or a pocket and more particularly it relates to vanity cases having means for distributing powder therefrom while the case is closed.

An object generally of the invention is the provision of novel means for distributing powder from a closed vanity case.

Another object of the invention is the provision in a vanity case, equipped with a distributing plate normally in contact with the contents of the case but capable of being partially withdrawn therefrom, of novel means operating to prevent leakage of powder underneath the plate.

A further object of the invention is the provision of novel means, in combination with a plate for distributing powder from a closed vanity case, whereby the actuation of the distributing plate breaks up incipient caking of the powder which sometimes occurs in the intervals between use, and thereby keeps the powder in finely pulverized disintegrated condition.

Still another object of the invention includes the provision of an article of the class described which is simple in construction, which can be readily and conveniently fabricated and assembled, which may be economically manufactured and which, in its construction, assembly and use provides improvements and conveniences not heretofore employed in the art for the same general purpose.

Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts,

Fig. 1 is a perspective view of a vanity case

embodimenting the device of my invention, the lid of the case being open and the powder dispensing device embodying said principles of my invention being extended in a position making a supply of powder available for use. 55

Fig. 2 is a longitudinal sectional view through the vanity case along the line 2—2 of Fig. 3; and

Fig. 3 is a transverse sectional view along the line 3—3 of Fig. 2. 60

Referring more particularly to the drawings, the invention is illustrated as embodied in a vanity case taking the form of a main rectangular container or receptacle having side walls 10, and a bottom wall 9. The container is provided with a lid or cover 11 fastened to the side wall 10 by a hinge construction 12. The lid 11 is held in its closed position as shown in Figs. 2 and 3, by a detent member 13 having one end projecting 70 through the front portion of the side wall 10 and having an upwardly and forwardly extending yielding portion 8, positioned to enter a recess or indentation 14 in the front flanged portion of the lid 11. A plate 15 is 75 mounted on the inner face of the lid 11 to form a mirror available for use as desired.

A frame structure is positioned within and closely fits the side walls 10 of the main rectangular container or receptacle. The frame structure comprises side walls 16 and a top plate 17 having a relatively large central aperture bounded by a downwardly and outwardly tapering flange 21. A plate 23, having an upwardly and outwardly extending flange 24, closely fits the aperture in the top plate 17 so as to form a cover for a space 22 enclosed by the frame. The plate 23 is removed when necessary to replenish the supply 80 of powder in the space 22 and the upper surface of the plate is polished to form an additional mirror. The side walls 16 of the frame structure may be welded or otherwise fastened to the side walls 10 of the main container in any desired manner. 85

The opposite longitudinally extending side walls 16 are provided with inturned bottom flanges 18 having raised edges 19. The space 95 underneath and between the raised edges 19 100

provides a runway in which a distributing plate 26 is slidably mounted. The longitudinal edges of the plate 26 fit the spaces underneath the raised edges 19 sufficiently close to prevent the leakage of the powder contents of the container, the arrangement being such as to permit the easy reciprocation of the plate. A partition wall 20 extends across the container in parallel and closely spaced relation to the front wall 10. The detent fastening member 13 is mounted in the space between the front wall 10 and the wall 20. The wall 20 prevents leakage of the powder contents of the container into the space in which the detent member 13 is mounted and avoids the possibility of the powder finding its way through the aperture in the front wall 10 through which the member 13 projects.

The distributing plate 26 projects through and closely fits an aperture 32 in the front wall 10 of the main container and is provided with a downwardly turned flange 27 by means of which the plate may be manually actuated and partially withdrawn from the container.

The lower edge of the partition wall 20 closely fits against the upper surface of the distributing plate 26 and prevents leakage of powder from the space 22 into the space between the partition wall 20 and the front wall 10.

The plate 26 is normally in the full line position of Fig. 2 in which substantially its entire upper face is in contact with the overlying powder contents of the container, and as the plate is withdrawn and retracted, there is a tendency for the powder normally adhering to the bottom of the container to work forwardly and underneath the plate and be discharged from the underside of the container. Such leakage is undesirable for obvious reasons and an important feature of the invention is the provision of novel means for removal of all the powder adhering to the bottom of the container in advance of the retractive movement of the plate 26. For this purpose a spring plate 29 is so mounted on the inner end of the distributing plate 26 that the free end of the plate 29 presses against the bottom 9 of the container and forms a scraper removing such powder as adheres to the upper face of the wall 9 as the plate 26 is retracted. The scraping of the bottom wall 9 with each retraction of the plate prevents the powder contents of the container from leaking between the plate 26 and the wall 9. A pin 30 provides a stop limiting the outward movement of the plate 26 and prevents accidental removal of the plate from the container.

The upper face of the plate 26 is provided with a plurality of transversely extending serrations 28. In extending the plate to the position shown in Fig. 1, corresponding to the dotted line position of Fig. 2, the partition wall 20 and the front wall 10 scrapes

all of the powder from the top surface of the plate except that contained within the serrations 28. The powder contained in the serrations 28 is thereby made available for use by means of a puff or the like. Any unused powder remaining in the serrations 28 is returned to the container upon retraction of the plate 26.

Novel means is provided whereby the movement of the plate tends to keep the powder contents in finely pulverized condition by breaking up any incipient caking of the powder which may occur between the intervals of use. This result is accomplished by positioning one or more transversely extending wires 31 in closely spaced relation to the upper surface of the plate 26. The wires 31 are spaced away from the plate 26 sufficiently to clear the projecting end of the stop pin 30. The reciprocation of the plate 26 in its runway pushes or pulls such hardened lumps or cakes as may have formed, between the wires and the top surface of the plate thereby crumbling and disintegrating the same.

Thus it will be seen that I have provided, in combination with a vanity case having means for distributing powder contents with the case closed, novel means for preventing leakage of the powder from the case and novel means adapted to disintegrate and neutralize any caking of the powder contents of the device.

Having thus described my invention, it is obvious that various immaterial modifications may be made in the same without departing from the spirit of my invention; hence, I do not wish to be understood as limiting myself to the exact form, construction, arrangement, and combination of parts herein shown and described or uses mentioned.

What I claim as new and desire to secure by Letters Patent is:

1. In a device of the kind described, a powder receptacle, the bottom wall of said receptacle having a smooth surface, a distributing plate normally in contact with the contents of said receptacle and capable of being partially withdrawn, said plate slidable in close contact with the bottom wall of the receptacle, and means projecting rearwardly from the plate adapted to scrape the bottom of the container as a result of the retractive movement of said plate.

2. In a device of the kind described, a closed powder receptacle, a distributing plate normally in contact with the contents of said receptacle and capable of being partially withdrawn, said plate slidable in close contact with one wall of the receptacle, and a spring plate projecting from the inner end of the distributing plate, the free end of the spring plate pressing against said wall to form a scraper.

3. In a device of the kind described, a

- closed powder receptacle, a distributing plate normally in contact with the contents of said receptacle and capable of being partially withdrawn, one side wall of said receptacle
 5 having an aperture through which the plate projects and closely fits, said plate slidable in close contact with the bottom wall of the receptacle, and a spring plate projecting from the inner end of the distributing plate, the
 10 free end of the spring plate pressing against the bottom of the container to form a scraper.
4. In a device of the kind described, a closed powder receptacle, a distributing plate normally in contact with the contents of said
 15 receptacle and capable of being partially withdrawn, said plate slidable in close contact with the bottom wall of the receptacle, a spring plate projecting from the inner end of the distributing plate, the free end of the
 20 spring plate pressing against the bottom of the container to form a scraper, and an intermediate transverse member positioned over said distributing plate in closely spaced relation to its upper face.
- 25 5. In a device of the kind described, a closed powder receptacle, a distributing plate normally in contact with the contents of said receptacle and capable of being partially withdrawn, one side wall of said receptacle
 30 having an aperture through which the plate projects and closely fits, said plate slidable in close contact with the bottom wall of the receptacle, a spring plate projecting from the inner end of the distributing plate, the
 35 free end of the spring plate pressing against the bottom of the container to form a scraper, and an intermediate transverse member positioned over said distributing plate in closely spaced relation to its upper face.
- 40 6. In a device of the kind described, a closed powder receptacle, a distributing plate normally in contact with the contents of said receptacle and capable of being partially withdrawn, said plate slidable in close contact with the bottom wall of the receptacle, a spring plate projecting from the inner end of the distributing plate, the free end of the
 45 spring plate pressing against the bottom of the container to form a scraper, and a plurality of wires extending transversely over said distributing plate in closely spaced relation to its upper face.
- 50 7. In a device of the kind described, a closed powder receptacle, a distributing plate normally in contact with the contents of said receptacle and capable of being partially withdrawn, one side wall of said receptacle having an aperture through which the plate
 55 projects and closely fits, said plate slidable in close contact with the bottom wall of the receptacle, a spring plate projecting from the inner end of the distributing plate, the free end of the
 60 spring plate pressing against the bottom of the container to form a scraper,
- and a plurality of wires extending transversely over said distributing plate in closely spaced relation to its upper face.
- In witness whereof, I hereunto subscribe my name this 7th day of October A. D. 1930. 70
 WALTER PORANSKI.
